PATIENT SUPPORTING AND CARRYING MEANS FOR OPERATING AND STRETCHER TABLES AND HOSPITAL BEDS

Edward T. Wicks, 133 3rd St., New City, N.Y.

Filed July 9, 1962, Ser. No. 208,377

4 Claims. (Cl. 5—81)

This invention relates to means for supporting hospital patients on operating and stretcher tables and hospital recovery beds and transferring them from the operating to the stretcher tables and from the stretcher tables to the recovery beds. This sequence may, of course, be reversed in transferring a patient from a hospital bed to a stretcher table and then to the operating table.

Essentially, the purpose which this invention proposes to solve is transferring patients, in no condition to be moved, from one place to another. It is a common practice today to handle and lift a hospitalized patient as many as six times during the course of his transfer from hospital bed to operating table and back. Not infrequently does this adversely affect the patient's condition. The problem is to move the patient from hospital bed to operating table and back again without unnecessary handling. Prior to surgery the patient is lifted from hospital bed to stretcher table and then from stretcher table to operating table and, following surgery, he is lifted from operating table to stretcher table and, finally, from stretcher table to recovery bed. These are the basic procedures but there are other handling procedures as well which add to the discomfort of the patient and sometimes adversely affect his condition.

The object of this invention is the provision of transferable means for supporting a patient on a hospital bed, stretcher table and operating table, said transferable supporting means being also adapted for transferring the patient from hospital bed to stretcher table and from stretcher table to operating table and back again, all of this without any unnecessary handling or lifting of the patient.

Specifically, the present invention comprises the combination of supporting rails on the hospital bed, stretcher and operating tables and pad or table sections movably supported on said rails. In use, a stretcher table may be placed adjacent a hospital bed or adjacent an operating table, the rails being axially aligned, and the pad or table sections may be moved along said rails from bed to stretcher table and from stretcher table to operating table, etc. This may be done with the patient on said pad or table sections and the same pad or table sections may support the patient either in bed or on the stretcher and operating tables.

The invention is illustrated in the accompanying drawing in which:

FIGURE 1 is a perspective view of a pivotally linked series of pad or table sections forming part of and used in connection with the present invention.

FIGURE 2 is a transverse section through one of said pad or table sections taken on the line 2—2 of FIGURE 1.

FIGURE 3 is an end view of said pad or table section.

FIGURE 4 is a transverse section through a railed support for said table sections or pads, said railed support being a stretcher or operating table or hospital bed or the like.

FIGURE 5 is an enlarged fragmentary transverse section through such railed support showing one of the pads or table sections mounted thereon and locked thereto.

FIGURE 6 is an enlarged fragmentary side view of one of the links joining adjacent pads or table sections.

FIGURE 7 is a fragmentary section on the line 7—7 of FIGURE 6.

2

FIGURE 8 is a fragmentary perspective view, partly in section, showing one of said pads or table sections slidably mounted on a pair of supporting rails.

FIGURE 9 is a perspective view of a stretcher table supporting a pair of parallel rails and adapted to serve as a railed support for the series of linked pads or table sections shown in FIGURE 1.

FIGURE 10 is a perspective view of an operating table on which a plurality of rails are mounted parallel to support said linked series of pads or table sections.

FIGURE 11 is a side view of the stretcher table shown in FIGURE 9 showing said linked pads or table sections mounted thereon and covered by a continuous pad.

FIGURE 12 is a fragmentary plan view of said stretcher table as shown in FIGURE 11.

FIGURE 13 is a section on the line 13—13 of FIGURE 12.

FIGURE 14 is a plan view of the operating table shown in FIGURE 10.

Referring now to the details of the invention as set forth in the accompanying drawing, it will be noted that a typical patient supporting and transferring means as herein claimed includes a plurality of table sections 10, 12, 14 and 16, which may be made in any predetermined dimensions and of any selected shape, materials and construction. Since the present invention is intended for hospital use it will, of course, be understood that hospital approved materials and designs are required for sanitary and other purposes. Since the present invention is intended to be applied to conventional operating tables, such as operating table 40 shown in FIGURE 10 of the drawing, the shape and size of these table sections and their spacing should correspond substantially to the shape, size and spacing of table frames 40a, 40b, 40c and 40d of said operating table. In this connection it will be understood that operating table 40 is simply an illustration of the many kinds of operating tables which are in conventional use today. The relative spacing of the table top frames of any conventional operating table and their respective shape and dimensions will dictate the corresponding specifications for the table top sections 10, 12, 14 and 16.

It will be noted in FIGURE 1 that the links 18 connect each adjacent pair of table top sections 10, 12, 14 and 16. These links are pivotally secured to said table top sections and they function not only to connect the several sections but also to space them from each other in predetermined relationship and permit them to pivot relative to each other. In this connection it will be understood that the several table sections or frames 24a, 24b, 24c, and 24d of operating table 40 are pivotally related to each other to permit of many different operating positions. Illustrative of these operating positions are those which are commonly known as the lithotomy, proctoscopic and laminectomy positions. Whatever position the operating table is adapted to assume is a position which the table sections 10 to 16 inclusive must also be capable of assuming.

Links 18 may be connected to the table top section 10 to 16 inclusive by any conventional means. However, it has been found desirable to permanently connect them at one end and to detachably connect them at the opposite end. Consequently, at one end, each of these links 18 is simply pinned, riveted or screwed to the table sections 10 to 16 and at the opposite end said links are provided with a hook-shaped portion which engages a screw in the table sections. A thumb nut or butterfly nut 20 may be applied to each said screw to prevent dislodgment of the hook-shaped end of the link from the screw which it engages. At both ends, however, each said link remains pivotally connected to one of said table sections. The advantage of the hook-shaped end is to

permit of disengagement of the several table sections 10 to 16 inclusive, from each other. The link construction is best shown in FIGS. 6 and 7 of the drawing.

It will be observed in FIGS. 2 and 3 that each table section 10, 12, 14 and 16 is provided with a pair of channels 22. Preferably, these channels extend longitudinally of each said table section, one along each side edge thereof. These channels are disposed in parallel relation to each other for a purpose and function which will shortly appear. The precise shape of these channels is not significant. A preferred shape is that of a longitudinally split cylinder, the split or opening facing downwardly.

Reference should now be made to FIGS. 4 and 5 of the drawing where it will be seen that a pair of rails 24 are mounted on a table top or frame 26 which may be the top of a stretcher table or any other movable or stationary support or carrying means for a patient. These rails 24 are shaped and spaced to correspond and complement the shape and spacing of channels 22, thereby permitting said channels to slide longitudinally upon said rails in order to assume their relative positions shown in FIGURE 5 of the drawing. These rails may be mounted on any suitable support such as supporting member 26 or any open frame member such as will shortly be described in connection with the stretcher and operating tables which are illustrated in the drawing.

Similar rails 24a, 24b, 24c and 24d may be mounted on frame sections 40a, 40b, 40c and 40d of the operating table 40. Similarly, rails 54 of like cross-sectional configuration may be mounted on frame 52 of stretcher table 50. The difference between rails 24a, 24b, 24c and 24d on the operating table and rails 54 on the stretcher table is that in the case of the operating table each pair of rails must be pivotally mounted with respect to the other pairs of rails, whereas on the stretcher table the rails may be fixed. See FIGS. 9 and 10.

In the use of the present invention a plurality of table top sections 10, 12, 14 and 16 may be placed upon rails 24 on a supporting structure 26. For purposes of illustration, said supporting structure may be assumed to be a hospital emergency table or bed or any other like structure. Mounted on said table top sections 10, 12, 14 and 16 may be a continuous pad 60 of any suitable material. The patient would lie upon said pad for examination or other purposes. On the assumption that a surgical operation is required, it would then be necessary to move the patient from said supporting structure 26 to the operating table 40. The table sections 10, 12, 14 and 16 would then be slid longitudinally from rails 24 to rails 54 of the stretcher table 50. This may be done by simply placing the stretcher table rails adjacent to and in alignment with rails 24 of the supporting structure 26. The table sections 10, 12, 14 and 16 could then be moved longitudinally onto rails 54 without disturbing the patient. The stretcher table would then be moved to a point adjacent one end of the operating table and rails 54 would be placed in alignment with rails 24a, 24b, 24c and 24d. The table sections 10, 12, 14 and 16 would then be moved once again, this time from rails 54 to rails 24a, 24b, 24c and 24d. Once again, there would be no disturbance to the patient and he would be brought into an operating position suitable for any operating procedure.

In connection with the operating procedure, it may be found necessary to pivot the several operating table sections 40a, 40b, 40c and 40d relative to each other and this would involve pivotally rearranging the positions of the table sections 10, 12, 14 and 16. To prevent accidental dislodgment of said table sections relative to said operating table frame sections, a locking means is provided as illustrated in FIGURE 5. Within each table section, is a locking mechanism consisting of a pair of locking bolts 30 and 30a mounted within a pair of collars or bearings 32 which are secured to channels 22. Connected to said bolts 30 and 30a is a pair of toothed bars 34 and 34a respectively, which engage a toothed wheel 36

on diametrically opposite sides thereof. Said toothed wheel is mounted on a shaft 37 to which a handle 38 is connected. It will be noted that collars 32 are aligned with holes 32a in channels 22 and that corresponding holes 32b are formed in rails 24. When these holes 32a and 32b are aligned, it is possible for bolts 30 and 30a to pass through them and thereby to lock the channels 22 and rails 24 against relative longitudinal movement. This may be effected by means of handle 38. When said handle is rotated in one direction, toothed bars 34 and 34a move outwardly toward the sides of the table sections and bolts 30 and 30a are thereby moved into locking engagement with rails 24. When the handle is rotated in the opposite direction said toothed bars move inwardly and said bolts are retracted from said locking engagement. It will be understood that this locking procedure may be effected on the stretcher table and operating table and on any other supporting structure on which the table sections 10, 12, 14 and 16 may be mounted. All that is needed is a series of holes 32b in the rails adapted to register with holes 32a in the channels.

The foregoing is illustrative of a preferred form of the invention and it will be understood that modifications may be incorporated therein without departing from the basic principles of the invention. For example, the rails and channels which ride on them may be of any desired cross-sectional configuration. The precise shape shown in the drawing is purely illustrative. The bed locking mechanism which is shown in the drawing is also purely illustrative and any other suitable locking mechanism may be used to prevent dislodgment of the table top sections with respect to their supporting rails.

What is claimed is:

1. Patient supporting and transferring means for patient supporting units such as hospital beds and stretcher and operating tables, comprising the combination of a plurality of segmented rails mounted on each of said units and a plurality of platform sections slidably mounted on the segmented rails of any one such unit for slidable movement onto the rails of any other of said units, each said unit being provided with a plurality of pairs of rails, the rails of each pair being disposed in spaced parallel relation to each other, and each said platform section being provided with a pair of parallel rail engaging bearings spaced for alignment with said pair of parallel rails, each parallel pair of rails of each unit being aligned with all of the other parallel pairs of rails on the same unit and the parallel rails of each unit being spaced for alignment with the parallel rails of any other unit, said platform sections being slidably movable on their respective rail engaging bearings from one pair of parallel rails to another on any one unit and from the parallel rails on any one unit to the parallel rails of any other unit.

2. The combination of claim 1 wherein each hospital unit is provided with four pairs of parallel rails, there being four platform sections adapted to be supported thereon.

3. The combination of claim 1 wherein the several platform sections are pivotally linked to each other.

4. The combination of claim 1 wherein locking means are provided between the rail engaging bearings of at least one platform section and at least one parallel pair of rails.
